UNITED STATES PATENT OFFICE.

WILLIAM H. PALMER, OF YALE, MICHIGAN.

SICKLE-BAR FOR HARVESTERS.

SPECIFICATION forming part of Letters Patent No. 443,791, dated December 30, 1890.

Application filed October 10, 1889. Serial No. 326,641. (No model.)

To all whom it may concern:

Be it known that I, WILLIAM H. PALMER, a citizen of the United States, residing at Yale, in the county of St. Clair and State of Michigan, have invented certain new and useful Improvements in Sickle-Bars for Harvesters, of which the following is a specification, reference being had therein to the accompanying drawings.

This invention relates to new and useful improvements in sickle-bars for harvesters; and the invention consists in the novel construction and arrangement whereby the sickles or knives are detachably secured to the sickle-bar, all as more fully hereinafter described, and shown in the accompanying drawings, in which—

Figure 1 is a plan of a section of a sickle-bar detached from the harvester. Fig. 2 is a longitudinal section thereof on line *x x*. Fig. 3 is a cross-section of a sickle-bar on line *y y* in Fig. 1, showing it in position as in operation. Fig. 4 is a cross-section of a sickle-bar with sickles of slightly-modified form. Fig. 5 is a plan view of a modified form of sickle-bar embodying my invention in another form. Fig. 6 is a cross-section thereof on line *w w*, and Fig. 7 is a detached plan of one of the notched sickles.

A represents a series of sickles or knives of the usual form. B is the sickle-bar to which they are secured; C, the finger-bar, and D the fingers in which the sickles operate as in the usual manner, except as hereinafter described.

My invention consists in the novel manner in which the sickles are secured to the sickle-bar, and to this end I use the following means: The sickle-bar I preferably make in two parts, which I secure together at intervals by rivets E, with an open slot equal to the thickness of the knives between them and extending the whole length of the bar. Into this slot the knives are assembled side by side and clamped against a fixed abutment at one end of the slot by a wedge F, driven in at the other end of the slot between the first knife of the series and the fixed abutment or rivet G. This wedge or key I secure in a substantial manner by a set-screw or otherwise, so that it will not be liable to become detached, except for the purpose of detach-

ing the knives from the bar. I preferably secure the rivets E, which secure the two parts of the sickle-bar together at intervals, 55 coincident with the width of three knives, so that one rivet passes between each third knife, allowing the wedge to act throughout the whole series of sickles to clamp them together, the edges of the knives adjoining the 60 rivet having notches H cut into them, as shown in Fig. 7, which notches have to be deep enough to prevent the sickles from binding upon the rivet. With a sickle-bar so constructed it will be seen that if it is desired to 65 remove the knives, for the purpose of grinding or otherwise, from the sickle-bar, the wedge being first loosened, every knife in the center of the three constituting a section can be driven out backwardly, as shown in dotted 70 lines in Fig. 1, and after it has been removed the two adjoining knives may be disengaged from the sickle-bar. Thus every section can be readily removed in the same manner. The mounting of the knives on the bar is then ac- 75 complished in the reverse manner, and after they are put in position side by side the wedge is then firmly driven in, so that all the knives crowd against each other against the abutment held between the fixed abutment at one 80 end and the end of the bar at the other. I do not intend to confine myself to this construction alone, as it is obvious that upon the principle I have now described many modifications may be made—such as, for instance, 85 that instead of one wedge to hold the whole series of knives, several wedges may be used, each one for a portion of the series of knives; and, further, to give more stability to the knives of the sickle-bar the knives may be 90 provided with a downwardly-projecting flange I at the rear end, as shown in Fig. 4, or as shown in Fig. 6, in which said flange extends to the under side of the sickle-bar. With a sickle-bar of this latter construction it will be 95 seen that my principle of clamping the knives in series may be applied with a single sickle-bar, as shown in Fig. 5, and that, instead of a wedge F for clamping, a screw J or other equivalent mechanical device for accomplishing the same end may be used.

My construction of sickle-bar has the advantage of great simplicity, which will be appreciated by those familiar with such devices.

Further, my construction makes use of the simplest form of sickles, and thus admits of interchangeability with almost any form of sickles used in the different styles or constructions of harvesters, provided the sickle has the right width; and, further, it will be seen that with my construction it will be practicable to remove any of the knives in case of emergency without dismounting the sickle-bar from the harvester. As, suppose the sickle-bar to be held in position in the usual manner, as shown in Fig. 3, it will be possible, without removing or turning the spring-plates K out of the way, that the rear edge of the sickle-bar may be sprung up sufficiently to dismount the knives in the manner before described. This is a decided advantage, as with most other constructions the sickle-bar has to be dismounted entirely, and thus a vexatious delay occurs.

A further advantage of my construction is that the whole series of knives, being clamped together in one body, there is no liability of any one knife becoming loose, and as there is but one locking device for the sickles the mounting and dismounting are quickly accomplished.

The rivets E, which secure the two parts of the sickle-bar together, are in the first place for the purpose of keeping the two bars in their proper relative position to each other; and it will be conceded, also, that they form an element of stability for the knives, as each rivet passing between two sickles will hold the same against displacement in the line of the draft.

What I claim as my invention is—

In a sickle-bar, a series of rivets or posts E and a series of knives arranged in groups of three between the posts, the outer knives of the groups having side grooves in their outer edges, in which the rivets enter, and the center knives having even edges, permitting an easy insertion of the same between the outer knives of the group, and a clamping device to secure the knives in place, substantially as described.

In testimony whereof I affix my signature, in presence of two witnesses, this 3d day of October, 1889.

WILLIAM H. PALMER.
